UNITED STATES PATENT OFFICE.

EDWARD F. GEHRKENS, OF PITTSFIELD, MASSACHUSETTS, ASSIGNOR TO GENERAL ELECTRIC COMPANY, A CORPORATION OF NEW YORK.

INDUCTION-FURNACE.

1,011,769.

Specification of Letters Patent. Patented Dec. 12, 1911.

Application filed July 14, 1910. Serial No. 571,898.

To all whom it may concern:

Be it known that I, EDWARD F. GEHRKENS, a citizen of the United States, residing at Pittsfield, county of Berkshire, State of Massachusetts, have invented certain new and useful Improvements in Induction-furnaces, of which the following is a specification.

My invention relates to electric furnaces of the induction type and involves a furnace in which the secondary current is largely induced in the walls of the furnace instead of entirely in the charge, the heat being communicated to the charge by conduction and radiation.

Induction furnaces have heretofore been built to induce a current in the charge itself. This design not only requires the charge to be conductive when the furnace is started but it has a further disadvantage. When a very heavy current is traversing the fluid charge, a phenomenon known as the "pinch effect" is apt to take place, the charge under the influence of electrical forces breaking its own circuit. The circuit may remain permanently broken by non-conductive slag lodging in the break. According to my invention this difficulty is overcome by providing as part of the furnace structure a secondary having a low resistance zone and a relatively high resistance zone, the high resistance zone forming part of the wall of the crucible or chamber containing the charge. The heat generated in the high resistance zone is communicated to the charge with which it is either in immediate contact, or separated only by a refractory lining.

My invention will be more fully described in connection with the accompanying drawings in which—

Figure 1 is a perspective view of a single phase induction furnace constructed in accordance with my invention; Fig. 2 is a plan view of a somewhat modified form; Fig. 3 is a diagram of connections, and Fig. 4 is a plan view of a three-phase furnace.

Referring to Fig. 1, the furnace crucible or melting chamber 1 consists of a metal shell 2, which in part forms the secondary of the furnace, as will be presently explained. The primary coils 3, 3 are wound on the iron core 4 and for single phase operation are connected in series or parallel, a series connection being shown in Fig. 3. The coils are shown in Fig. 3 as being con-

nected to the secondary of a feeding transformer 5, to represent any source of energy. The secondary "windings," as they may be called, surrounding the primary coils consist of some refractory metal such as steel, or an alloy consisting of sixty-two parts nickel, nineteen parts iron, eleven parts chromium, and eight parts manganese. This alloy is known as calorite. Each secondary has a massive relatively low resistance zone 6 and zone 7 of smaller cross-section and hence of relatively high resistance. The inside surface of the furnace chamber 1 may be covered with a suitable refractory insulating lining but this may in some cases be omitted, especially when a relatively low melting point metal is to be melted in the furnace, such as brass or aluminium. The spout 8, provided with a suitable plug, serves for the removal of the melted charge.

When an alternating current is impressed on the primary windings of the furnace, a current is induced in the usual well understood manner in the secondary windings surrounding the same. Very little heat is generated by the passage of this current in the relatively low resistance part of the secondary 6, the heat being chiefly generated in the high resistance portion 7. No current will flow in the walls 9, 9' connecting the two turns of secondary as these walls form part of a circuit entirely inclosing all of the legs of the magnetic system when taken as a unit by itself. A very low voltage is generated in the secondary windings and, therefore, even when no lining is provided to insulate the charge from the secondary, very little current is diverted from the same by the charge as this current would encounter two contact resistances which are relatively considerable at the very low voltage, especially when the interior surface of the furnace crucible is oxidized.

In some cases it is advisable to construct the high resistance part of the crucible as a complete shell surrounding the primary windings and connected by side walls to form a charge-receiving chamber. A relatively massive wall, or jacket, consisting of some suitable metal of high conductivity is cast around the high resistance wall so as to be in direct metallic contact therewith at the outer portion of the furnace. This form is illustrated in the furnace shown in Fig. 2, the high resistance part of the furnace

being indicated by the portion 10 and the low resistance massive part by the portion 11. The same construction may, of course, be used with a three-phase, or any other design of furnace, a three-phase furnace being illustrated by Fig. 4. In either of the modifications, the only part of the circuit to which voltage and current is induced is that part which completely surrounds one leg of the magnetic circuit. The low resistance massive portion 11 will reduce the heating in the portion 10 throughout the region in which it is in contact with the same by shunting current therefrom.

It will be readily seen from the above description that in no case can the electrical circuit in which the secondary current is flowing interrupt itself by breaking its circuit according to the "pinch effect."

What I claim as new, and desire to secure by Letters Patent of the United States, is:—

1. In an induction furnace, the combination of a charge-receiving chamber, a primary, and a secondary inductively related thereto and having zones of unequal resistance, a zone of relatively high resistance forming part of said charge-receiving chamber.

2. In an induction furnace having a charge-receiving chamber, the combination of a primary, and a secondary inductively

related thereto, said secondary consisting of a metallic shell having zones of unequal cross-section and corresponding unequal resistance, the zone of higher resistance forming part of said charge-receiving chamber.

3. In an induction furnace, the combination of a primary inductive winding, a secondary winding surrounding the same, and a charge-receiving chamber, a section of the walls of said chamber forming a portion of said secondary winding.

4. In an induction furnace having a charge receiving chamber, the combination of a primary winding and a secondary winding surrounding the same consisting of a conductive wall, including a section of relatively high resistance which forms a part of the charge-receiving chamber.

5. In an induction furnace having a charge-containing crucible, the combination of a primary winding, and a secondary winding in inductive relation therewith, said secondary having a zone of relatively high resistance, said zone forming part at least of said crucible.

In witness whereof, I have hereunto set my hand this 12th day of July, 1910.

EDWARD F. GEHRKENS.
